UNITED STATES PATENT OFFICE.

EDGAR T. HORSEY, OF CLEVELAND, OHIO.

DEVICE FOR USE WITH HEADLIGHTS.

Application filed December 5, 1921. Serial No. 519,920.

To all whom it may concern:

Be it known that I, EDGAR T. HORSEY, a citizen of the United States, residing at Cleveland, in the county of Cuyahoga and State of Ohio, have invented a certain new and useful Improvement in Devices for Use with Headlights, of which the following is a full, clear, and exact description.

The present invention relates to a device 10 adapted to be used in association with the front lens or glass of a headlight such as is customarily used upon automobiles.

One object of the invention is to provide a device which will effectively prevent glare 15 in connection with the use of headlights, while interfering to a minimum degree with the efficiency of the light stream projected from the lamp.

A further object is to provide a device 20 which may be manufactured and sold at low cost.

Reference should be had to the accompanying drawings forming a part of this specification, in which Fig. 1 is a plan view 25 of a device embodying my invention; Fig. 2 is a plan view of a modified construction; Fig. 3 is a plan view of a co-operating sheet which is adapted to be used in preparing the form of the device shown in Fig. 2 for 30 use.

Referring to the drawings, 1 indicates a sheet of material forming the body portion 35 of the device. The sheet may be made of paper or any suitable material as celluloid, isinglass, linen, cloth, in fact, any material which may be made to assume sheet form. This disk is provided with an opening 2 which opening lies entirely below a line 40 passing through the center of the sheet 1 and the opening is disposed symmetrically with respect to an axis which extends through the center and at right angles to the first mentioned line. This opening is bounded by curved edges. The top of the 45 opening may be described as a compound curve, while the lower edge of the opening is a simple curve. This opening of the form which is herein disclosed has been found particularly efficient for use as a glare preventing device in connection with headlights 50 where the lamp furnishing the light is in proper focus. The body of the sheet 1 which surrounds the opening 2 is preferably translucent but not transparent, or, in other 55 words, light may pass through the body of the disk 1 which surrounds the opening 2,

but the glare will not be present. This arrangement is desirable inasmuch as the whole surface of the headlight is illuminated with the exception of a shaded area which 60 will be subsequently described, which gives a more pleasing effect, and additionally the light which passes through the translucent portion of the member 1 serves to throw a diffused light on the road in front of the 65 automobile which is sufficient for lighting the road in the immediate vicinity of the front wheels.

At the upper part of the member 1 there is a band 3 which is relatively opaque, this 70 band extending a little short of 180°.

Where the material of which the member 1 is composed permits, it is advantageous to print the shaded area 3 upon it.

At the lower half of the member 1 there 75 are a series of concentric half circles such as indicated at 4. These circles represent the principal diameters of lens or glass fronts for headlights, which are most generally in use. In preparing such a sheet as 1 for 80 installation in a headlight, the sheet is laid flat and the glass or lens of the headlight is positioned over the sheet and is adjusted on the sheet until the edge or circumference of the glass of the headlight coincides with its 85 proper semi-circle, as represented at 4. When this is accomplished then the glass or lens may be used as a means for guiding a cutting instrument for trimming away the 90 extra or excess material of the sheet 1 which would lie outside of the periphery or edge of the glass.

After the sheet has thus been trimmed to the proper diameter then it is caused to adhere to the inner face of the glass or lens of 95 the headlight.

This may be accomplished by having the surface of the sheet 1 prepared with adhesive substance which upon being moist 100 becomes in condition for attaching the sheet to the lens or glass, or on the other hand, a suitable layer of cement or other adhesive material may be applied to the sheet or the glass at the time it is positioned on the lens or glass.

When the sheet and the glass or the lens 105 have thus been assembled, the same is placed within the lamp and is ready for use.

In connection with this device, as in any other it is necessary that the electric lamp 110 bulb or source of light be adjusted so that it is as near the correct focus as is possible

to get the same, but assuming that the source of light is correctly focused, then the rays of light reflected by the reflector will in a diffused way pass through a portion of the device, that is to say, the translucent portion surrounding the opening tube.

Additionally, the light which directly will strike against the inner portion of the disk 1 will again be reflected and a part of the 10 same, together with a portion of the light directly reflected by the reflector will pass out through the opening 2, thus forming a direct beam of light which projects in front of the headlight for a considerable distance, while the diffused light passing through the translucent portion of the disk 1 will illuminate in the immediate vicinity of the headlight.

In Fig. 2 the same form of disk 1^a with 20 its opening 2^a and opaque strip 3^a is shown, but in this form there are no circle or peripheral lines such as indicated at 4.

These lines are omitted in the modification shown because in certain instances some 25 of the lines will show through the glass of a headlight where the form of device as shown in Fig. 1 is used. That is to say, where the diameter of the glass is greater than the diameter of the smallest circle such as indicated at 4.

In the form of device which is shown in Fig. 2 this contingency is eliminated.

At 5 is indicated a sheet which is provided with a plurality of quarter circles, such as 35 indicated at 6, and each of these quarter circles is of a different diameter. The sheet is also provided with an area 7 which is bounded by curved lines of precisely the same form as the opening 2^a.

40 In preparing the sheet 1^a which is customarily provided to be slightly greater than the largest diameter of glass or lens customarily in use, the sheet 5 is overlaid on the sheet 1^a so that the enclosed portion 7 corresponds and registers with the part 2^a. Then the glass is laid upon the sheet 5 and the periphery of the glass is brought into registration with the quarter circle corresponding with its diameter. When this is 45 done the excess material of the sheet 1^a and incidentally of the sheet 5 is trimmed away by a suitable sharp instrument. The sheet 5 can then be removed, and thus the sheet 1^a is trimmed to be of proper diameter and 50 may be secured to the glass or lens of the

headlight by means of any suitable adhesive which adhesive may have been previously applied at the time when the sheet 1^a is made up, or may be directly applied at the time of its usage. As stated earlier in the 60 specification, the disk may be made of any material. Paper has been found to be a very suitable substance from which to make the disk, although no limitation is intended in this respect. Where paper or cloth is 65 used it will be advisable to waterproof the same.

Having described my invention, I claim:—

1. A device of the character described comprising a disk-like member adapted for 70 association with the open end of a reflector said disk having an opening through it which opening lies below the transverse center line of the disk said opening having a curved periphery at the portion which is 75 remote from the center of the disk and having a compound curved periphery at the portion which is adjacent the center of the disk, the portion of the disk surrounding the opening being translucent but not transparent, said disk having an arc-shaped band and a portion thereof which is oppositely disposed with respect to the opening, said arc-shaped band being opaque to the passage 80 of light.

2. A device of the character described comprising a disk-like member adapted for association with the open end of a reflector said disk having an opening through it which opening lies below the transverse center line of the disk said opening having a curved periphery at the portion which is 90 remote from the center of the disk and having a compound curved periphery at the portion which is adjacent the center of the disk, the portion of the disk surrounding the opening being translucent but not transparent, said disk having an arc-shaped band and a portion thereof which is oppositely disposed with respect to the opening, said 95 arc-shaped band being opaque to the passage 100 of light, a portion of said disk adjacent the periphery being provided with a plurality of concentric lines which are arcs of circles for the purpose of positioning the said sheet 105 upon a glass or lens of a headlight.

In testimony whereof I hereunto affix my signature.

EDGAR T. HORSEY.
